S. B. TULLOSS

SORTING CASE

Filed Oct. 5, 1922

*Inventor,
Stuart B. Tulloss
by
H. Bowditch -
Attorney.*

UNITED STATES PATENT OFFICE.

STUART B. TULLOSS, OF WASHINGTON, DISTRICT OF COLUMBIA.

SORTING CASE.

Application filed October 5, 1922. Serial No. 592,588.

My invention relates to sorting cases or files, and more particularly to a device for sorting slips such as bank checks or the like.

5 The object of the invention is to provide a simple, compact and readily operated device for sorting slips such as bank checks that have been received or collected out of order as to serial number or other individual 10 identifying marks.

A particular object of the invention is to provide a device of the above qualifications especially adapted for use where the checks are to be sorted according to an individual 15 serial number and where a large number of checks is to be sorted in a batch in which the serial numbers differ by a thousand or less.

In the handling of great numbers of 20 checks as in the filing of checks paid by the Government or large corporations, it is found that of each thousand checks received for filing, about 95 per cent have serial numbers which are within the same thousands 25 group, that is, differ by less than a thousand units. This makes it most economical to sort them in batches containing all those of a common thousands group amounting to approximately a thousand or about 950 30 checks to the batch.

The present practice, in sorting by hand, is to make a preliminary sorting of the checks into batches containing all those belonging to a common thousands group, each 35 of which batches, approximating 950 checks, is then arranged in serial order by three sorting operations. First, they are thrown in hundreds groups which necessitates handling the whole batch of checks to sort those 40 differing by one hundred and which first throwing would result in ten groups of hundreds; secondly, each group of hundreds is thrown in tens groups, and thirdly, each tens group is thrown in units. Thus, the 45 whole batch of nearly a thousand checks must be handled three times.

With applicant's device, the batch of approximately one thousand checks resulting 50 from the preliminary sorting, and containing, for example, checks whose serial numbers range from 2,674,000 to 2,674,999, may be arranged directly in serial order with but one handling of the checks.

55 My invention is illustrated in the accompanying drawings, in which:

Fig. 1 is an orthographic projection of my device, on a reduced scale;

Fig. 2 is a fragmentary projection, approximately actual size, of the top front portion;

Fig. 3 is a fragmentary detail view, on the scale of Fig. 1, of the first leaf in a group of fifty;

Fig. 4 is a similar view of a leaf near the middle of a fifty group;

Fig. 5 is a similar view of the last leaf in a fifty group;

Fig. 6 is a fragmentary detail section through the lower portion of the cards showing the spacing strips;

Fig. 7 is a transverse section through the lower right hand side of the device;

Fig. 8 is a fragmentary view, in projection and substantially actual size, of a modified form of my device.

Referring to the drawings in detail, the base portion 1 is a tray-like structure comprising a bottom member 2, side members 3 and 4, and end members 5 and 6.

In this base are vertically set a thousand and one partition leaves or cards 7 alternating with a thousand spacing strips 8. The spacing strips 8 run substantially the length of the cards and extend substantially as high as the sides 3 and 4. The whole series of partition leaves and spacing strips are tightly bound together within the base by means of the end members 5 and 6 which are arranged to be drawn up to the ends of the side members by the bolts 9 to exert a clamping action on the leaves and strips. The bolts 9 operate by threading into nuts 10 nested in the side members. The purpose of this tight clamping or binding is not only to hold the leaves and strips in the base but to hold the leaves 7 and strips 8 in contact throughout their juxtaposed surfaces, regardless of whether or not the leaves are bent or flexed away from each other as indicated in Fig. 6. Thus each strip 8 is made to form the bottom wall of a compartment whose side walls may be flexed or bent away from each other without separating from the bottom wall. To further guard against outward displacement of the leaves and strips, I provide an inwardly projecting locking bead 11 on each side member 3 and 4, as indicated in section in Fig. 7, which engages with notches 12 in the strips and leaves.

It will be seen that the structure just described forms a group of one thousand check compartments in a very compact and sturdy unit. These compartments are numbered serially by numbering the partition leaves, in the present instance, 000 to 999, and to aid in quickly finding and opening up a particular compartment to enable a check to be placed therein, I provide a novel arrangement of indexing and operating means which will now be described.

The front partition leaf 7 is simply a cover or front leaf for the first compartment, while the remaining one thousand partition leaves 15 7 are provided with raised index portions or tabs 13 numbered 000 to 999 from the front rearwardly. The leaves are divided into twenty groups of fifty, the first leaf in each group having an index tab on the 20 extreme left such as the tabs numbered "000", "050", "100", etc., as indicated in Figs. 1, 2 and 3. The index tabs of the remaining forty-nine leaves in each group of fifty are spaced progressively to the extreme right hand end a distance of one digit so as to show the units digit, excepting the first leaf in each group of ten, after the first leaf of a fifty group, which have their index tabs 14, numbered "010", "070", 25 "180", etc., raised clear above the others and spaced just sufficiently to the right of the overlapping tab to show a distinct break, preferably of contrasting color, at the beginning of a ten group.

35 All the index tabs 13 are of the same height and in order to make them clearly visible from the front of the device without depriving them of the support afforded by the leaves back of them, I so shape 40 the upper edges of the leaves that they form elements of a plane extending from the upper edges of a row of tabs 13 in one fifty group to the bottoms of the tabs of the next succeeding fifty group, as clearly shown in Fig. 2 where it will be seen that the top surface of the mass of leaves is notched. For obvious reasons, the tops of the leaves in the first fifty group extend horizontally along the base line of the tabs so that the 45 plane 15 formed by this group is horizontal.

To effect this formation of the surface of the mass of leaves, I form the upper edges, as shown in Figs. 3, 4 and 5, with a slant upwardly from the right hand side 55 of the tab and downwardly from the left hand side of the tab, the height of the corners of the leaves varying according to their positions in the group.

It will be noted that the tabs 14 form 60 four columns of whole serial numbers which are clearly distinguishable from the other numbers and tabs 13 by their extra height and contrasting color. The purpose of this is to enable the operator to readily find 65 the beginning of any group of ten. To

clearly mark off the beginning of each fifty group, I make the first leaf and tab, "050", "100", "150", etc., of a contrasting color different from the first leaves of the tens group other than those beginning with fifties and hundreds. 70

A modified form of my invention consists in making the leaves 7 of transparent material with the serial numbers below the edges of the leaves in the same order as that 75 of Figs. 1 and 2, as indicated in Fig. 8. The top edges of the leaves thus form a plane surface as shown, on which are marked numbers as at 16 and 17 indicating, respectively, the fifty-groups and tens-groups. To further set out the columns of tens-groups 80 I mark a line 18 of a distinctive color across the top edges of the leaves between the tens-groups over the last digits (the ciphers) of the number of the leaves beginning a tens-group. To make the leaves beginning a fifty-group more readily distinguishable, I make such leaves, those numbered "050", "100", "150", etc., of a distinctive color so that the top edge of each 85 will present a line 19 of a distinctive color marking the beginning of a fifty-group. 90

In operation, with the preferred form as shown in Figs. 1 to 7, the operator simply picks up a check, the serial number of which is noted to end in say 185, glances up the tens column containing the 80's, which from experience he knows to be the third, and places the thumb of his right hand against the first "5" tab to the right 100 of the "180" tab in the third column. As this "5" tab is on the leaf numbered "185" forming the rear partition of the compartment for the check whose serial number ends in 185, the leaf is pushed back, opening up the compartment sufficient to enable the check to be dropped therein. While this is the mode of operation which is thought to be the most efficient, being the one which an operator soon adopts after 105 some experience, other modes of operation may be practiced according to the choice of the operator. An obvious method that might appeal to a beginner in placing the check numbered 185 would be to first glance 110 up the column of fifty-groups to the highest fifty-group which would be 150 and glance along the tens tabs to the right, past "160" and "170", on to "180" and from thence to the next tab numbered "5". 115

The operation of the modified form shown in Fig. 8 is substantially the same as that just described except that in finding a compartment, say number "060", the operator places his thumb at approximately the intersection of the lines of ciphers 18 and the beginning of the second fifty-group, pushing back the leaves and permitting a few to slip forward until the one numbered "060" appears. 120

While I have thus illustrated and described certain specific embodiments of my invention for the sake of disclosure, it is to be understood that I do not limit myself thereto, but contemplate all such modifications and variants thereof as fall fairly within the scope of the appended claims.

What I claim and desire to secure by Letters Patent is:

- 10 1. A sorting case comprising a base member having sides and movable end members forming a tray, partition leaves and spacing strips arranged alternately in said base or tray extending from side to side and 15 extending as a pack of leaves from end to end of the tray, and means for clamping the said movable end members against the ends of the pack to bind said leaves and strips together.
- 20 2. A sorting case comprising a series of partition leaves having index tabs bearing index numbers individual to the leaves raised above the top edges of several leaves immediately in front and positioned progressively from left to right on successive leaves from front to back and extending laterally of each other an amount only sufficient to show a portion of the number near the units end whereby the exposed tab area 25 is reduced to less than the sum of the areas occupied by the whole index numbers.
- 30 3. A sorting case comprising a series of partition leaves having thumb tabs raised above the top edges of several leaves imme-

dately in front and positioned progressively 35 from left to right on successive leaves from front to back in a plurality of groups of leaves to form a plurality of rows of tabs extending from left to right and spaced from front to back, the top edges of the leaves of 40 a group being shaped to form a plane extending from the top line of a given row of tabs to the base of the succeeding row of tabs.

4. A leaf or card index comprising a series 45 of cards having tabs extending upwardly from the top edges of the cards and positioned progressively from left to right and from front to back, each bearing a group of characters and extending sufficiently to the 50 right of the one in front to show the last character only of the said group of characters, certain of said tabs being raised sufficiently above the level of the other tabs to show the whole group of characters. 55

5. A leaf or card index comprising a series of cards, having tabs extending upwardly from the top edges of the cards and positioned progressively from left to right and from front to back to form a plurality of 60 diagonal rows of index tabs, each tab being backed by a backwardly and downwardly extending buttress formed of the upper portions of the cards between it and the next succeeding row of tabs. 65

In testimony whereof I affix my signature.

STUART B. TULLOSS.
